UNITED STATES PATENT OFFICE

1,978,067

HIGH POWER SHORT WAVE TRANSMITTING APPARATUS

Carl Vrany, Berlin-Lichterfelde-Ost, and Heinrich Zodtner, Birkenwerder, near Berlin, Germany, assignors to C. Lorenz Aktiengesellschaft, Berlin-Tempelhof, Germany

Application November 3, 1931, Serial No. 572,796
In Germany November 5, 1930

5 Claims. (Cl. 250—17)

The present invention relates to high power short wave transmitting apparatus, and more particularly to an improved form of construction of the apparatus. Hitherto, transmitters have been built up on metal frames in which the electron discharge valves and tuning members were arranged. Such a construction, however, has the disadvantage that, owing to the many metal parts, the capacity to earth is very great and the connecting leads cannot be made short enough. The necessity for a small capacity to earth and short connecting leads, becomes more important as the wave-length is decreased, but it is desirable that these demands should also be met when using medium wave-lengths.

An object of the invention is to provide a high power short wave transmitting apparatus in which the elements are supported upon a single pillar of insulating material.

20 Another object is to provide an insulating pillar for supporting the elements of a high power short wave transmitting apparatus in which is incorporated a channel for the supply of cooling fluid to the electron discharge tubes employed in said transmitting apparatus.

Another object is to provide a hollow pillar for this purpose through the interior of which current supply leads pass to the elements of the short wave transmitting apparatus.

30 Another object of the invention is to provide a plurality of pillars of insulating material each of which supports a plurality of electron discharge tubes and which support conjointly further elements which constitute with said electron discharge tubes a short wave generating set.

Still another object of the invention is to provide a pillar of insulating material carrying the elements of a high power short wave transmitting set which is provided with shoulders upon which rest the electron discharge tubes employed in said short wave generating set.

40 Further objects will be apparent from the following description taken in conjunction with the accompanying drawings in which:

Fig. 1 illustrates diagrammatically a circuit arrangement which may conveniently be employed in the apparatus according to the invention.

50 Fig. 2 shows an elevation of one form of the apparatus.

Fig. 3 shows another view partly in section of the apparatus shown in Fig. 2.

55 Fig. 4 is a plan view of the apparatus shown in Figs. 2 and 3.

Fig. 5 shows a modified form of the invention in elevation.

Fig. 6 is an adaptation of the apparatus shown in Fig. 1.

In Fig. 1, the final stage of a high-power transmitter employing eight tubes is illustrated diagrammatically the grid circuits being omitted for the sake of clearness, only the anode circuits being shown. The tubes, 1 to 8, are connected in such a manner that pairs of tubes (1 and 2, 60 3 and 4, 5 and 6, 7 and 8) are connected in parallel. The connection is moreover effected through the inductance coils 9 to 12 and the condensers 13 and 14. The neutralizing condensers 15, 16, 17 and 18 have plates common with these 65 condensers. The input of the generated oscillations is effected through the inductance 19, by inductive coupling with the coils 11 and 12. The anode voltage is applied at the point 20.

70 In the constructional example illustrated in 75 Figures 2, 3 and 4 of the accompanying drawings, the various components are indicated by the same reference numerals as their corresponding symbols in Figure 1. On a pedestal 21 (Figs. 2 and 3) of insulating material (preferably stoneware or porcelain) there rests a pillar 22. It is, of course, possible to make the parts 21 and 22 in one piece. In the example illustrated, the walls of the pedestal 21 have special passageways formed therein through which the anode cooling water flows. 80 Since the city water mains or other sources of cooling water are usually at ground potential the cooling water path must be sufficiently long to isolate the plate battery. These spiral passages are formed in the insulating material to provide 85 a column of water to isolate the tube anodes from ground. To this end, spiral passageways for the cooling water are formed in the round body. The cooling water enters at the point 23 and is supplied to the individual tubes through spiral channels 90 which are indicated diagrammatically. At the upper end, connections 24 and 25 to the anodes of the tubes are provided for this purpose. The tubes themselves are mounted directly on the fixed plates of the anode tuning condensers 13 and 14 95 so that additional connecting leads between the anode cooling jacket and the fixed plates of the condensers are dispensed with. The condensers themselves are directly fixed to the pillar 22. To this end, the pillar 22, as can best be seen from 100 the plan view in Fig. 4, has arms 26 to which the condensers are fixed. The shafts of the rotors are mounted in the insulating material at the points 27. A very compact construction is thus obtained and no special connecting leads are used. 110

The movement of the rotors is effected by means of a worm wheel drive operated by a common shaft. Since the fixed plates of the condensers are arranged parallel to one another, the rotors 5 do not interfere with one another. The clearance of the condensers can therefore be kept small and is determined only by the thickness of the arms 26. The neutralizing condensers are fixed to the arms in the same way, as can best be seen 10 from Fig. 3. The plates 29 of the anode condensers, as mentioned above, are common with the fixed plates for the neutralizing condensers. The coupling coil 19 is likewise rotatably mounted in arms 31 (Fig. 4) of insulating material. 15 A roof-shaped metal screening sheet 32 (Fig. 3) which screens the anode circuits from the grid circuits is provided, mounted in the upper part of the pillar 22. In order that the electron tubes may be interchangeable, the outer edge of the 20 metal sheet may be hinged. The head 33 of the pillar, also has arms in which the grid-circuit condensers and the grid-circuit tuning members are mounted, but this mounting is only diagrammatically illustrated in the drawings. It is preferable not to make the head 33 in one piece with the pillar, but to attach it thereto. As can be seen in Fig. 4, the interior of the pillar 22 is made hollow, so that the current supply leads (anode potential) may be passed up inside. 25 A modification of the invention, embodying improvements upon the arrangement described and particularly suitable for discharge tubes of very high power, for instance, 150 kw. will now be described. According to this feature of the invention, the clamps or the like by which the tubes are fixed to the porcelain pillar in the construction shown in Figs. 2 to 4, are replaced by arms with which the pillar is provided and on which the tubes and other heavy parts of the transmitter 30 rest. It is then necessary only to protect the tubes from falling over. This arrangement has the advantage that the entire weight of the tubes is borne by the arms and that metal fixing members, which would otherwise be necessary, are dispensed with. 40

A constructional arrangement is shown by way of example in Figs. 5 and 6. The pillar S is provided on its lower portion with arms A on which the anode cylinders of the discharge tubes R stand. 45 In order to prevent the tubes falling over, the clamps L are provided. As can be seen from Fig. 5, the upper portion of the pillar S thereby becomes very narrow, by which means it is also possible to economize in material. On the head of the pillar are arranged the grid-circuit members G which are screened off; furthermore, measuring instruments may be provided, as indicated diagrammatically in the figure. 50

In Fig. 6 is shown the side view of an arrangement where two pillars are arranged side by side. Such an arrangement is provided for instance, when two normally operating tubes and two reserve tubes are provided. In this case it is of advantage, according to a further feature of the invention, to support the transmitter parts, for instance, as illustrated, the grid circuits G by both pillars at the same time. 80

We claim:—

1. High power short wave transmitting apparatus comprising the combination of a short wave generating set including at least one electron discharge tube, and a pillar of insulating material supporting said set, said pillar incorporating a channel for the supply of cooling fluid to the electron discharge tube. 85

2. High power short wave transmitting apparatus comprising the combination of a pillar of insulating material, electron discharge tubes mounted on said pillar, said pillar incorporating a channel for the supply of cooling fluid to the anodes of said electron discharge tubes, condenser plates mounted in parallel relation on said pillar, said tubes being directly secured by 100 their anodes to said condenser plates. 90

3. High power short wave transmitting apparatus comprising the combination of a pillar of insulating material, electron discharge tubes having fluid cooled anodes, said pillar incorporating a channel for the supply of cooling fluid to said anodes, a plurality of projecting arms on said insulating pillar, and rotatable tuning members journaled in said projecting arms. 105

4. High power short wave transmitting apparatus comprising the combination of a short wave generating set including electron discharge tubes having fluid cooled anodes, a hollow pillar of insulating material supporting said set, the walls of said pillar incorporating a channel for the supply of cooling fluid to said anodes and current supply leads passing through the interior of said pillar. 110

5. High power short wave transmitting apparatus comprising the combination of a hollow pillar of insulating material, a plurality of condenser plates arranged in parallel relation on said pillar, electron discharge devices supported by their anodes on said condenser plates, the walls of said pillar incorporating a channel for 120 the supply of cooling fluid to the anodes of said electron discharge tubes, and current supply leads passing through the interior of said pillar. 125
